INVENTOR

James O. Brown

UNITED STATES PATENT OFFICE.

JAMES O. BROWN, OF BANGOR, MAINE.

TRUNK-FASTENER.

SPECIFICATION forming part of Letters Patent No. 248,700, dated October 25, 1881.

Application filed June 22, 1881. (No model.)

To all whom it may concern:

Be it known that I, JAMES O. BROWN, of Bangor, in the county of Penobscot and State of Maine, have invented a certain new and useful Trunk-Fastener, of which the following is a specification.

My invention relates to an improved device for fastening the lids of trunks, &c., the object being to make a simple, cheap, and secure device, which may be always reliable and easily worked. I attain these objects by the mechanism illustrated in the accompanying drawings, in which—

Figure 1 is a plan view, showing the device entire, the catch being secured in its place on the plate. Fig. 2 is a plan view, showing the two parts separated. Fig. 3 is a vertical section. Fig. 4 is a horizontal section taken on the line *xx* of Fig. 1.

Similar letters refer to similar parts throughout the several views.

A represents the part that is to be made secure to the lid, and *D* the part that is to be secured to the body of the trunk.

The latch proper, *B*, is provided with short pintles at *a a*, which fit into corresponding sockets made in the part *A*, so as to form a hinge for the latch *B*. The latch *B* is narrowed at *b b* (see Fig. 2) and terminates in a broad end, *B'*. (See Figs. 1 and 2.) The end *B'* is turned up slightly, and is chamfered on its under side, as shown in Fig. 3.

H is a cross-latch, which is pivoted to the pin *P*, Figs. 1, 2, and 3, and is provided with a small wedge-shaped projection, *h*, Figs. 1 and 2.

E and *E'* are bosses formed on the surface

of the plate *D*, their shape and size being shown in Figs. 2 and 4. The upper side of the boss *E'* is kerfed, as indicated at *K*, Figs. 2 and 4, to for the purpose of receiving and holding the end of the cross-latch *H*.

S, Figs. 1 and 3, is a bent spring attached to the under side of the latch *B*, the bent part of which projects through the hole *C*, Figs. 1 and 2, in the latch *B*, and serves to hold the cross-latch *H* in place. (See Fig. 1.)

From the above description it will be understood that when the latch *B* is down the bosses *E E'*, fitting into the recesses *b b*, Fig. 2, will prevent the latch from being drawn out, and if the cross-latch *H* is in place, as shown in Figs. 1 and 3, it (the latch) cannot be removed, and the trunk is consequently securely fastened. When the cross-latch *H* is swung entirely back the wedge-projection *h* slides under the end *B'* of the latch *B* and forces it up away from the bosses *E E'*.

I claim—

1. In a trunk-fastener, the combination of the plate *D*, bosses *E E'*, and cross latch *H* with the plate *A* and latch *B*, having recesses *b b*, all operating together substantially as described, and for the purpose set forth.
2. In a trunk-fastener, the combination of the plate *D*, bosses *E E'*, cross-latch *H*, and projection *h* with the latch end *B'*, all operating together substantially as described, and for the purpose set forth.

JAMES O. BROWN.
